UNITED STATES PATENT OFFICE.

CYRUS W. SALADEE, OF TORRINGTON, CONNECTICUT.

TWO-WHEELED VEHICLE.

SPECIFICATION forming part of Letters Patent No. 270,700, dated January 16, 1883.

Application filed September 14, 1882. (No model.)

To all whom it may concern:

Be it known that I, CYRUS W. SALADEE, a citizen of the United States, and a resident of Torrington, in the county of Litchfield and 5 State of Connecticut, have invented certain new and useful Improvements in Volantes or Two-Wheeled Vehicles, of which the following is a specification.

My invention is an improvement in "volantes" 10 or two-wheeled vehicles, whereby to secure the advantage of a drop-front body, a ready change of the angle of the body, an easy spring-support, and to permit shafts or a pole to be used, as desired.

15 In the drawings, Figure 1 is a side elevation of a volante embodying my invention. Fig. 2 is a half-plan view of the running-gear, the body removed. Fig. 3 is a detached side view of the spring carrying the front end of the body. Fig. 4 is a detached sectional view, showing the shackle and cross-bar. Fig. 5 is a side elevation of a volante, showing a modification. Fig. 6 is a half plan view of the same. Figs. 7 and 8 are front views of the 25 front cross-bar of the frame in Figs. 5 and 6, showing the arms whereby to adjust the relation between the shafts or pole and frame to regulate the "hang" of the body.

One feature of my invention is designed to 30 secure the application of a phaeton or "drop-front" body A in this class of vehicles. By elevating the rear ends of the shafts, side bars, or frame, and by arranging the springs, side bars, or shafts, all as shown in the drawings, 35 a means is provided for the application and use of drop-front bodies in a two-wheeled vehicle, with the drop-fronts below the axles. The front end of the body is suspended from longitudinal springs L, the rear or heavy ends of 40 which are connected to the axle C, whereby the front end of the body is relieved from that up-and-down tipping motion common in these vehicles. The front end of each spring L is provided with an eye, L', to receive the pintle 45 of a shackle-joint. The shafts or the side bars of the frame are secured to the axle C by means of the shackle-joint D, or otherwise. An under brace, F, Fig. 1, has its rear end secured by a shackle-joint, G, to the under side of the 50 axle, or at any suitable point below the shackle-joint D. Its front end is united below the bottom of the shaft B to an adjustable clip, H.

By adjusting the clip H back or forth on the shaft B the front ends of the shafts are raised or lowered in their relation to the body, so that 55 the latter may be maintained level or horizontal whether a tall or small horse is used. Other means of adjusting the body in the frame may be employed. The shafts or side bars of the frame are connected by the cross-bars K and 60 P'. The elevated rear end of the body is supported by suitable springs. I prefer two longitudinal springs, M, their heavy or inner ends being firmly bolted to the body, and their outer ends bent down, passing round the cross-bar 65 P' and united to shackles N; but I do not limit my claims to the precise arrangement and combination of spring shown in the drawings, as it is obvious that other forms and kinds of springs may be adapted to the frame and body 70 shown to answer a like purpose, or nearly so.

It is often desirable to have a vehicle which may be used with either shafts or a pole. To secure this I make the frame with side bars, B², Fig. 5, of the same form as the frame shown 75 in Figs. 1 and 2. Either shafts B or a pole, X, dotted lines, Fig. 6, may be secured to the axle C at the points G.

The body may be provided with adjusting devices to alter its level upon the frame. In 80 Fig. 7 an arrangement suitable for use with shafts is used. In Fig. 8 a pole-adjusting device is shown. In either case the pole X or shaft B is connected by a link or links, F', (corresponding in effect to the link P, shown 85 in Fig. 1,) to an adjustable clip, H', upon some part of the frame. The adjustment of the clip alters the angle of the body, as before described.

The device Fig. 7 is substituted for that 90 shown in Fig. 8 whenever the change is made from shafts to pole.

I do not limit my claim to the adjusting devices here shown. Many other devices well known in the state of the art may be substituted therefor.

I claim—

1. In a volante or two-wheeled vehicle, a phaeton or drop-front body supported upon four longitudinally-arranged springs, two extending from the axle to the body and two from the body to the frame, substantially as set forth.

2. In a volante or two-wheeled vehicle, a

phaeton or drop-front body supported at the front and rear upon flexion springs, the front springs extending forward from the axle and the rear springs extending from the body to the frame, as set forth.

3. In a volante or two-wheeled vehicle, the frame connected directly to the axle, and body suspended on springs therein, in combination with an adjusting device to set and hold the axle and the shafts in the desired relation to regulate the hang of the body, as set forth.

4. In a running-gear for a volante or two-wheeled vehicle, the frame whereon to support

the body, consisting of side bars and cross-bars uniting them, in combination with a pole or shafts extended from the axle and connecting with the front end of the frame, substantially as set forth.

In testimony whereof I have signed my name to this specification in the presence of two subscribing witnesses.

CYRUS W. SALADEE.
